US00D527661S

(12) **United States Design Patent** (10) Patent No.: **US D527,661 S**
Liu (45) Date of Patent: ** Sep. 5, 2006

(54) **LASER LEVEL**

(75) Inventor: **Yi Liu**, Jiangsu (CN)

D499,032 S * 11/2004 Khubani D10/69

* cited by examiner

(73) Assignee: **Nanjing Chervon Industry Co., Ltd.**,
Nanjing (CN)

Primary Examiner—Antoine D. Davis
(74) Attorney, Agent, or Firm—Butzel Long

(**) Term: **14 Years**

(57) **CLAIM**

(21) Appl. No.: **29/236,479**

The ornamental design for a laser level, as shown and described.

(22) Filed: **Aug. 17, 2005**

DESCRIPTION

(30) **Foreign Application Priority Data**

Mar. 24, 2005 (CN) 200530081610

FIG. 1 is a front elevational view of the design;
FIG. 2 is a rear elevational view of the laser level in FIG. 1;
FIG. 3 is a left side elevational view of the laser level in FIG. 1;
FIG. 4 is a right side elevational view of the laser level in FIG. 1;
FIG. 5 is a top plan view of the laser level in FIG. 1;
FIG. 6 is a bottom plan view of the laser level in FIG. 1; and,
FIG. 7 is a perspective view of the laser level of FIG. 1.

See application file for complete search history.
